MAXWELL ALPERN, OF PHILADELPHIA, PENNSYLVANIA, ASSIGNOR TO AMERICAN
ENGINEERING COMPANY, OF PHILADELPHIA, PENNSYLVANIA, A CORPORATION
OF PENNSYLVANIA.

DUMPING APPARATUS FOR STOKERS.

1,293,588.

Specification of Letters Patent. Patented Oct. 11, 1921.

Application filed December 27, 1918. Serial No. 268,458.

To all whom it may concern:

Be it known that I, MAXWELL ALPERN, a citizen of the United States, residing in Philadelphia, Pennsylvania, have invented a Dumping Apparatus for Stokers, of which the following is a specification.

One object of my invention is to provide a novel combination of parts whereby the dumping plates or other ash and clinker supporting structures forming part of a stoker of the inclined underfeed type, may be actuated by power with a view to making possible the use of larger and heavier structures, more particularly dumping plates of greater dimensions than hitherto with a view to lengthening the intervals between successive dumpings of ashes.

Another object of the invention is to so dispose the controlling means for the dumping apparatus of a stoker that the operator may directly observe the results of the actuation of the apparatus.

I further desire to provide novel means for mechanically shaking or agitating and dumping at will the ashes and clinkers collecting on the dumping plate of a stoker particularly of the inclined underfeed type;—the arrangement of parts being such as to be capable of cutting the clinkers from the bridge wall of the furnace.

It is also desired to provide a dumping plate of such design that it shall better resist the heat of the ashes and clinkers as well as better withstand the mechanical stresses to which it is subjected, than has hitherto been the case in similar devices.

Another object of my invention is to provide stoker dumping mechanism which in addition to being more easily operated than has hitherto been possible, shall include means whereby the controlling means for the dumping plate and that for the plate supporting member may be conveniently actuated from one point at which the interior of the stoker furnace may be observed.

These objects and other advantageous ends I secure as hereinafter set forth, reference being had to the accompanying drawings, in which,

Figure 1 is a side elevation, partly in section, illustrating my invention as applied to an inclined underfeed stoker; and

Fig. 2 is an elevation of the controlling

levers and their supporting stand forming part of the construction shown in Fig. 1.

In the above drawings, 1 represents a portion of a boiler setting, one at least of whose side walls 2 is provided with an observation opening or window 3. Mounted within this furnace and carried on a suitable frame work of which the members 4, 5 and 6 are illustrated, is a stoker of the inclined, underfeed type having a suitable inclined grate 7—8 mounted over a wind box 9 and supplied with fuel from a hopper 10 by suitable mechanism such as plungers operating in properly spaced cylinders which open into retorts (not shown).

It is noted, however, that the lower section 8 of the grate is mounted upon a base plate 11 whose rearmost edge is spaced some distance from the rear vertical or bridge wall of the boiler setting. This space between the plate and the rear wall opens into an ash pit 12 and is normally closed by a dumping plate 13 made in any number of sections, pivoted on or hinged to a shaft or spindle 14 extending transversely of the stoker and carried in bearing brackets 15 supported by the frame member 6.

This dumping plate which may be arranged in various ways and may be perforated without departing from my invention, is normally maintained in a closed, substantially horizontal position by a pawl 16 fixed to a spindle 17 rotatably mounted in the bridge wall and capable of being projected under the free edge of said plate at will by means of an operating arm 18 connected to the lower end of a controlling lever 20 by means of a link 19.

For operating the dumping plate I provide a motor in the form of a steam or air cylinder 21 which in the present instance is shown as suspended in the ash pit from the frame member 5. Said cylinder has fixed to it a guide 22 in which is slidably a cross head 23 connected through a piston rod 33 with the piston 34 of said cylinder;—said cross head, through a suitable rod 24, being connected to an arm 25 fixed to a shaft 26 carried in bearing brackets 27 projecting from the transversely extending frame member 6. This shaft 26 has also fixed to it any suitable number of operating arms 28 connected through links 29 with the dump plate 13, and it is obviously imma-

5 material whether one or more cylinders with their associated parts be connected with the shaft 26, since this would depend upon the dimensions of the stoker and the work required.

10 The cylinder illustrated is provided with a conduit 30 connected to a source of fluid under pressure through a pipe 32 in which is mounted a three-way cock 35 whereby the flow of motive fluid to and from the front end of said cylinder may be controlled. An exhaust pipe 31 is connected to the cylinder at such a point adjacent its rear end as to be uncovered by the piston and permit escape 15 of motive fluid after said piston has been moved rearwardly from its normal position shown, to a sufficient extent to swing the plate 13 upwardly through an angle sufficient to cause its inner or rear edge to cut from 20 the wall 1 any clinkers adhering or fused thereto. The movable member of this valve has an operating arm 36 connected through a link 37 to an arm 38 fixed to a shaft 39 and the latter like the shaft 17, projects beyond the side wall 2 of the boiler setting 25 where it has fastened to it an arm 40 connected through a link 41 to a controlling lever 20^a. This latter is fulcrumed coaxially with the lever 20 on a stand or bracket 42 in 30 such position that it may be manipulated by an operator when the latter is standing in a position such that he may be able to examine the interior of the stoker through the window or opening 3.

35 The inner or rear edge of the dumping plate is relatively sharp where it extends adjacent the bridge wall and the operating mechanism is so designed that said plate may swing upon the shaft 14 above its normal position illustrated without dumping the ashes carried by it, as well as swing down into a substantially vertical or steeply inclined position in which the ashes are discharged into the pit 12.

40 45 Under conditions of operation ashes and clinkers are allowed to collect upon the plate 13 until a predetermined quantity has accumulated, at which time the operator, by swinging the free end of the lever 20 toward 50 the vertical, so turns the valve or cock 35 that the motive fluid is admitted to the front end of the cylinder 21. The resulting movement of the piston 34 is comparatively sudden and violent, causing the dumping plate 55 to be swung upwardly, it being noted that the conduit 31 enters the cylinder at such a point that a sufficient volume of compressed air or steam is trapped at its rear end to properly cushion said piston at the end of 60 such rearward movement.

65 This upward swinging of the dumping plate not only cuts from the adjacent face of the bridge wall any clinkers or ashes which may have fused thereto but very effectually shakes up the mass upon it so as

to insure the thorough combustion of any fuel still remaining therein.

The rearward movement of the lever 20 to the position shown will allow the steam to exhaust from the front end of the cylinder 70 so that the dumping plate will fall back on the pawl 16 and the subsequent forward and backward movement of said lever will cause the dumping plate to be oscillated as above described any desired number of times so 75 that the ashes and clinkers may be shaken up to any required extent.

80 When it is desired to dump the ashes accumulated on the plate 13, the lever 20^a is moved forwardly from the position shown, 85 thus through the link 19 and arm 18, swinging the pawl 16 into its recess in the bridge wall, whereupon the dumping plate is allowed to fall by gravity into a vertical position so that it discharges the ashes into the 85 ash pit. Thereafter the forward movement of the lever 20 from the position shown admits motive fluid to the front end of the cylinder and causes the plate 13 to be raised to or above the position shown, whereupon 90 by means of the lever 20^a the pawl 16 is swung out into position to support said plate.

95 With the arrangement shown the operator is thus enabled to conveniently cause operation of the heavy dumping mechanism required in large capacity furnaces and may observe the results of the shaking and cutting action of the dumping plate as well as its discharge of the ashes into the pit.

100 The detail construction of the dumping plate is of course immaterial since it may be perforated in some instances and in other cases may be imperforate. Obviously also the detail mounting and arrangement of the 105 plate may also be widely varied without departing from my invention which has to do more particularly with the means for actuating and governing the position of the plate as well as with the arrangement of the controlling device whereby the results of the 110 operation may be conveniently observed.

115 I claim:

1. The combination in an underfeed stoker of an inclined grate; a dumping plate 115 at the lower end of said grate; power operated mechanism for moving the plate independently of the grate; a hand operated member for controlling said mechanism; and a manually controlled device independent of the power operated mechanism for normally retaining the plate in an ash carrying position and operative to release said plate when it is desired to dump the ashes thereon.

2. The combination in a stoker of a grate; 125 a dumping plate; a pawl normally supporting said plate in an ash retaining position; a power actuated device operatively independent of said pawl for swinging said plate above its normal position to shake up the 130

ashes thereon without dumping them; with means for withdrawing the pawl from its plate supporting position when it is desired to dump the ashes.

5. 3. The combination in a stoker of a grate; a dumping plate mounted adjacent thereto; a movable element normally supporting said plate in an ash retaining position; power operated means for swinging said plate, connected thereto independently of the supporting element; and controlling members for the plate supporting element and said plate swinging means respectively.
10. 4. The combination in a stoker of a dumping plate; a pawl normally supporting said plate in an ash carrying position; a fluid motor for operating the plate; motor controlling means including a manually actuated member; and a member operatively connected to the pawl independently of said controlling means for actuating it at will.

15. 5. The combination in a stoker of a grate; a dumping plate mounted adjacent the lower end of said grate; an inclosing setting having a window adjacent one end of said plate; means for swinging the plate; a member extending adjacent said window for controlling the operation of the plate swinging means; with a manually controlled device independent of the plate swinging means and also adjacent the window for normally maintaining said plate in its ash supporting position.

20. 6. The combination in a stoker of an inclined grate; a dumping plate hinged adjacent the lower end of said grate; a member mounted to engage and normally support the free edge of the plate; power operated means for swinging the plate; an operating device connected to raise said plate from a dumping to its normal position; and independent means for moving the supporting member into and out of its operative position.

25. 7. The combination in an underfeed stoker of an inclined grate; a substantially vertical wall spaced away from the lower end of said grate; a dumping plate hinged adjacent the lower end of the grate having a cutting edge movable in the arc of a circle substantially tangent to the vertical face of said wall;

power actuated means for turning the plate to cause its edge to forcibly cut clinkers from the wall face; with a manually operative member normally supporting the plate in an ash carrying position and movable into a cavity in the wall to release the plate.

30. 8. The combination in a stoker of a grate; a dumping plate mounted adjacent said grate; a movable element normally supporting the plate in an ash retaining position; power operated means for swinging the plate to agitate the material thereon and connected thereto independently of the supporting element; with adjacent manually operative members for governing the operation of the plate supporting element and said swinging means respectively.

35. 9. The combination in a stoker of a vertical wall having a cavity therein; an inclined grate; a dumping plate mounted to swing on a horizontal axis adjacent the lower end of said grate; power operated mechanism for swinging the plate; a pawl movable into the cavity in the wall and normally supporting the plate in an ash retaining position; with two coaxially supported, manually operative members for respectively controlling the pawl and the power operated means.

40. 10. The combination in a stoker of an inclined grate; a bridge wall; a dumping plate pivotally mounted in a position to normally support a body of ash between said wall and the grate; with a power actuated device including means operative to raise said plate to its normal ash supporting position and also to cause it to swing above such position to break up clinkers.

45. 11. The combination in a stoker of an inclined grate; a bridge wall; a dumping plate pivotally mounted in position to normally support a body of ash between said wall and the grate; a power operating device connected to said plate; and controlling means for said device operative to cause the plate to be swung above its normal ash carrying position to cut clinkers from the bridge wall and also to cause said plate to move from an ash-dumping position to its normal ash supporting position.

In witness whereof I affix my signature.
MAXWELL ALPERN.
